EXTRUDED BAKERY PRODUCT

Francis E. Porambo, Scotch Plains, N.J., assignor to Franchett's Kruellers, Inc., Elizabeth, N.J.

Filed June 15, 1960, Ser. No. 60,968

Term of patent 14 years

(Cl. D8—1)

FIG. 1 is a top plan view of an extruded bakery product showing my new design, the bottom face being plain and unornamented,

FIG. 2 is an end view thereof, all the sides presenting a similar appearance.

The dominant features of my design reside in the substantially square shaped extruded bakery product disclosed having vertical rows of markings on the upper face thereof and wherein the ornamented top portion has rounded sides that overlap the bottom portion, all as shown and described.
